UTILITY POLE SHELF CHANNEL GAIN

Joseph W. Dimiceli, 417 Eccles Ave.,
South San Francisco, Calif. 94080

Continuation-in-part of abandoned design application Ser.
No. 273,059, July 19, 1972. This application Nov. 14,
1973, Ser. No. 415,586

Term of patent 14 years

Int. Cl. D13—03

U.S. Cl. D8—230

FIG. 1.

FIG. 2.

FIG. 1 is an isometric view of the utility pole shelf channel gain of my invention.

FIG. 2 is a perspective diametrically opposite to the view shown in FIG. 1 of the utility pole shelf channel gain of my invention.

This is a continuation-in-part of design application Ser. No. 273,059, filed July 19, 1972, now abandoned.

I claim:

The ornamental design for a utility pole shelf channel gain, as shown.
